SERVICE STATION DISPLAY DEVICE

John R. Webb, Wilmette, Ill., assignor to Standard Oil Company, Chicago, Ill., a corporation of Indiana

Application January 25, 1952, Serial No. 268,309

1 Claim. (Cl. 40—125)

This invention relates to a service station display device and more particularly to a price display sign having a readily removable jacket and readily replaceable price display tags. It is conventional in gasoline service stations to employ a metallic curb sign frame embodying an upstanding display frame having a central yoke open at the top within which yoke is mounted a display plate, usually pivotally mounted within the frame. Gasoline prices or other display matter is mounted on each face of the plate.

Gasoline prices are normally displayed in cents and tenths of a cent, requiring three different numerals. In times of more stable prices, the price signs were of semi-permanent form; but for a number of years the rapidly fluctuating prices have placed an undue burden on gasoline station attendants.

The present invention comprises a very simple display device by which the station attendant can readily display any possible price for his gasoline and at the same time not deface or injure his display frame or display plate.

The invention is illustrated in the drawings in which:

Figure 1 is a front elevation of a conventional frame; Figure 2 is a similar view of the frame with a cardboard jacket thereover;

Figure 3 is a similar view of the frame with the price display placards in place; and

Figure 4 is a side elevation taken along the line 4—4 in Figure 3.

As shown in the drawings, the device comprises a yoke 10 open at the top and having mounted therein a display plate 11 which is held in the yoke by the pins 12. Over the yoke is a jacket 13, normally of cardboard or the like and if of cardboard preferably weather-proofed or weather resistant. This jacket is preferably secured both to the plate 11 and the frame 10 by wires 14 extending through grommets 15 in the jacket and secured to the frame 10.

The jacket has marginal projections 20 in its upper portion which extend laterally beyond the frame member. Within the upper portion defined by these projections are 55

2

mounted at least three generally rectangular placard members 21, each bearing a single numeral. Preferably grommets 22 are provided in each corner of the placard members, together with corresponding aligned openings in one side only of the jacket. Cotter pins 23 or other readily removable fastening member may be used for this purpose. If a cotter pin is employed, it should be one which will readily spread on being inserted in the opening, inasmuch as the openings do not go through both sides of the cardboard.

The display kit comprises a complete series of numerals for each of the placards. That is, there are ten placards for each group, each placard bearing one numeral from 0 to 9. It is usually sufficient, however, for the first placard to supply only the numerals 1, 2 and 3.

Normally, the display placards will be mounted on both sides of the display frame so that the sign can be seen from either direction.

The area 25 below the placard area affords a space for advertising copy which can be secured thereto in any of the usual ways.

The foregoing detailed description has been given for clearness of understanding only and no unnecessary limitations should be understood therefrom, as modifications will be obvious to those skilled in the art.

I claim:

A gasoline service station display device comprising a metallic upright display frame having a central yoke member open at the top, a permanent display plate 30 mounted within the frame, a T-shaped, weather resistant, envelope-like jacket, the vertical portion of said T-shaped jacket being open along its periphery and covering the display plate and the horizontal portion of said T-shaped jacket extending vertically above the display plate 35 and laterally beyond said yoke member, a plurality of mounting openings along the periphery of the vertical portion of said T-shaped jacket, mounting means extending through said mounting openings in the vertical portion of said T-shaped jacket whereby the jacket is 40 attached to the frame, a plurality of rectangular placard members aligned side by side in the horizontal portion of each side of said T-shaped jacket, a plurality of mounting openings in each placard member, aligned openings in the side of the jacket adjacent each such placard, and readily removable mounting means extending through 45 said aligned openings to mount the placards in readily removable form on the display device.
